CLAIM

The ornamental design for a massage stone heater with oil warmer, as shown and described.

DESCRIPTION

FIG. 1 is a front perspective view of a massage stone heater with oil warmer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front perspective view thereof showing the covers are opened.

The broken lines in the drawings depict portions of the massage stone heater with oil warmer that form no part of the claimed design.

1 Claim, 8 Drawing Sheets
